INVENTOR:

ATTORNEY.

UNITED STATES PATENT OFFICE.

JOHN F. LYONS, OF WEST SPRINGFIELD, MASSACHUSETTS.

FOLDING BOX.

Application filed March 19, 1921. Serial No. 453,590.

To all whom it may concern:

Be it known that I, JOHN F. LYONS, a citizen of the United States of America, and a resident of West Springfield, in the county of Hampden and State of Massachusetts, have invented a new and useful Folding Box, of which the following is a specification.

My invention relates to improvements in folding boxes of the type that is shipped flat and erected by the purchaser, and consists of a blank cut and creased in a certain peculiar manner, whereby the same can be arranged and folded to form a rectangular box body having a permanently attached cover, which cover can be used as a means for supporting said body at an incline, and also having a projector or extension for advertising matter, and being provided with card-holding means, all as hereinafter set forth.

The primary object of my invention is to produce out of a single piece of material, which has been properly cut and creased, a box adapted to hold various kinds of material or merchandise, such as candy for example, and completely enclose the same, on the one hand, or to be opened and set up for the display of its contents, on the other hand, such box having sufficient strength safely and securely to hold its contents, or, in other words, not being liable to come apart so that the contents will drop through or out of the box body, unless the same when open be turned bottom-side-up.

This box is comparatively simple and inexpensive to manufacture, can be easily and quickly set up, and when set up is locked together in such a manner that the shape and stability of the box are maintained, as intimated above, and can be opened conveniently and arranged for display purposes.

Another object is to provide a box of this character with sufficient area and adequate means for advertising purposes.

Other objects and advantages will appear in the course of the following description.

I attain the objects and secure the advantages of my invention by the means illustrated in the accompanying drawings, in which—

Figure 1 is a plan of a blank out of which may be formed a box that embodies a practical form of my invention; Fig. 2, a perspective view of a box formed out of the aforesaid blank, showing said box closed;

Fig. 3, a perspective view of said box when open and set up for display purposes; Fig. 4, an enlarged, transverse, vertical section through the closed box, and, Fig. 5, an enlarged longitudinal, vertical section through the closed box, the central portion thereof being broken out.

Similar characters of reference designate similar parts throughout the several views.

With reference to the blank shown in Fig. 1, it is desired to state that the full lines between sections or parts indicate cuts or slits, while the broken lines between sections or parts indicate scorings or creases.

It will be observed that the aforesaid blank has a generally angular formation and is divided and partially divided or separated by slits and creases, respectively, into different sections, parts, or members which are erected, folded, and otherwise arranged to form the box and the individual elements thereof. The blank may be said to consist of two main sections or divisions, one including the box-body elements and indicated by the letter A, and the other containing the box-cover elements and indicated by the letter B. The blank is positioned in Fig. 1 so that the division A is vertical and the division B is horizontal. The division B extends to the right from the right-hand edge near the top of the division A, the two being partially separated by a vertical crease *a* and short slits *b* at the ends of said crease.

The vertical division A comprises an intermediate vertical section 1, a horizontal upper section 2, and a horizontal lower section 3. The section 2 is set off from the section 1 by a horizontal slit 4 and a vertical crease 5, and said section forms a separator, spreader, or spacer for the box body. The section 3 is set off from the section 1 by horizontal slits 6 and 7 and an intervening horizontal crease 8, and a vertical slit 9 at the right-hand end of said section 3. In line with the top and bottom edges of the section 2 are creases 10—10 which extend to the ends of the crease *a*, and there are two similar creases 10 in line with the top and bottom edges of the section 3, the latter creases extending to the right-hand edge of the division A which is below said crease *a*. The section 1 has therein two creases 11, and two other creases 12 and 13, respectively. The right-hand crease 11 extends between the two inner horizontal creases 10, and the

same is continued downwardly at 14. In line with the slit 7 and the adjacent crease 10, and between the two, is a short slit 15. A long narrow part 16 is set off by the 5 crease 14. The creases 12 and 13 are continued downwardly across the section 3, such extensions being indicated by the numerals 17 and 18, respectively. A long narrow part 19, similar to the part 16 is set off by the 10 crease 18.

Beyond or above and below the two outer creases 10 the division A is extended to form two tabs 20. The part designated by the 15 numeral 21 forms the box-body bottom, the parts designated by the numeral 22 form the box-body sides, the parts designated by the numeral 23 form the box-body ends, the parts designated by the numerals 24 and 25 form separators, spreaders, or spacers, 20 the spacer 24 being comparatively wide and the spacer 25 comparatively narrow, and the part designated by the numeral 43 also forms a comparatively wide separator, spreader, or spacer. The parts 16 and 25 19 constitute comparatively narrow separators, spreaders, or spacers similar to the spacer 25. The tabs 20 are at the unattached terminals of the ends 23. The section 3 constitutes a flap which is designed 30 to receive advertising matter.

The horizontal division B comprises a large section 26 and two smaller sections 27. The sections 27 are set off from the section 26 by two horizontal parallel slits 28, and 35 vertical creases 29—29 which are in line with each other. Extending between adjacent ends of the slits 28 and the creases 10 that are in alignment with such slits are longitudinal or horizontal creases which are divided by and in turn divide a transverse or vertical crease, so that there are two long creases 30 and two short creases 31, and a long crease 32, and two short creases 33. In the section 26 is a crease 34 that connects the creases 29, all being in the same straight line, also a crease 35 that is parallel with the crease 34 and to the right thereof. There is a notch or recess 36 in one of the sections 27, which recess opens through 40 the outer longitudinal edge of such section. At the outer terminal of the section 26, beyond the crease 35, is a part that forms a separator, spreader, or spacer 45, and at the outer end of such part or spacer is a tongue 50 37. The parts of the section 26 that extend from the crease 34 to the crease 34 constitute the box-cover top 38, the same being jointed at and by the transverse crease 32, and the parts of said section that extend from the 55 slits 28 to the creases 29 constitute the box-cover sides 39—39, these being jointed also at and by the transverse creases 33. The part of the top 38 to which the major portion of said top is jointed at 32 is designated by the numeral 40, and the parts of

the sides 39 to which the major portions of said sides are jointed at 33—33 are designated by the numeral 41. The part designated by the numeral 42 forms an end of the cover. The sections 27 form separators, spreaders, or spacers. One terminal of the box cover being attached to the box body, there are end members only at the other terminal of said cover. The cover sides 39 and 41 are narrow especially at 75 the ends which are near the slits 28 and the creases 33. At the other ends the side pieces 39 are wider and approach in width the height of the cover end 42. As a matter of fact, however, the greatest width of 80 either side piece 39 is somewhat less than the height of the end 42.

The blank thus cut and creased is formed into a box in the following manner:

The cover of the box may be formed before the body of said box is formed, or the formation of said cover can be left until after said body has been formed, and I will here explain the formation of the latter before taking up the formation of the former.

To produce the cover, first bend up the sides 39 and 41 on the creases 30 and 31, respectively, then turn in the sections 27 on the creases 29 until said sections are 95 at right-angles to said sides, taking care that said sections are relatively arranged so that the one with the recess 36 therein is inside of the other, next turn up the end 42 on the crease 34 outside of said sections, 100 and finally turn the spacer 45 over the exposed edges of said sections and down inside of the recessed section, and tuck the tongue 37 through the recess and between adjacent portions of said sections. It will 105 be remembered that the sections 27 serve as spacers at the free end of the cover. The cover is now complete and ready for use either in its normal capacity or as a support.

To produce the body of the box, first 110 erect the side 22 that is at the right-hand edge of the section 1, by turning it up on its crease 11, and swing the end 23, to which the cover is attached, on the crease 10 that is between said end and said side, toward 115 the bottom 21 and until said end is at an approximately right-angle to said side, at the same time sliding the spacer 2 into place on said bottom; next swing the opposite end 23 on the crease 10 that is between said 120 end and said side, toward said bottom and until said last-named end is in approximately parallel relation with said first-named end, with the spacer 16 on said floor in line with said spacer 2; and then erect the opposite 125 side 22 by turning it up on its crease 11, turn the wide spacer 24 on the crease 12 over the top edge and down on said last named side, with the narrow spacer 25 on top of said spacer 2, and at the same 130

time turn the wide spacer 43 on the crease 8 into approximately parallel relation with the contiguous end 23 and thrust said last-named spacer down until it with the narrow spacer 19 comes to rest on said spacer 16. Before erecting the second side 22, the tabs 20 are swung inwardly at the free ends of the end members 23 into line with each other, and they are confined between said 10 side and the spacer 24. The spacers 25, 16, and 19 are bent into angular relationship with the side 22, the end 23, and the spacer 43, with which said first-named spacers are respectively connected, swinging on the 15 creases 13, 14, and 18, respectively. The body is now complete and the box ready for use. The cover may be extended beyond the end of the body with which said cover is directly connected, and rest at the free 20 end on the same support with said body, and the flap 3 may be extended upwardly and outwardly from the top of the spacer 43.

To close the box, turn the flap 3 downwardly on the crease 17 until said flap occupies an approximately horizontal position, and swing the cover on the crease *a* up, over, and down until the top 38 rests on the upper edges of the body and such edges are enclosed or embraced by the sides 39 and 41 and the end members which include the end 42. The joint at *a* closes the body of the box at that end. To uncover the box, simply swing open the cover on the joint *a*, and elevate the flap 3.

To locate the cover when open where it will be out of the way, and also to utilize said cover as a support for the body, which support is of a character to enable said body 40 with its contents to be displayed to the best advantage, it is merely necessary to fold said cover over the end of said body to which said cover is directly attached, and under the bottom of said body, as shown 45 in Fig. 3. In doing this the side pieces 41 are bent inwardly on the creases 31 and 33, and the side pieces 39 are also bent inwardly at their points of juncture with said side pieces 41, but from such points said side 50 pieces 39 gradually turn downwardly and outwardly until they assume vertical positions. The top of the cover, or that portion of the same that bears the numeral 38, is now under the bottom 21 of the body, while 55 the top piece 40 is over one end 23 of said body, and all is supported on the joints at 33 and the joint at 35, with the edges of the sides 39 and 41 clear of the flat surface on which the box is placed. Necessarily the 60 joint at 35 now is lower or extends below the flaps 27, and, since the width of the ends of the side pieces 39 to which said flaps are jointed is less than the width of the end 42, it follows that said joint must become the 65 direct support at that end for the folded

and inverted cover and the superimposed body. Thus the body of the box, or the box as a whole in fact, is supported at an incline with the folded side pieces 41 at what is now the front end of said body before it had 70 been the rear end. The advertising or display flap 3 is in the inclined position previously described, having been swung into such position on the crease 17, where the printed matter thereon is exposed to the best 75 advantage. The folded side pieces 41 form a holder for a card or similar display member, which can readily be slipped in between said side pieces and the contiguous end 23, at the top, and as readily slipped out. A 80 card 44 is represented in Fig. 3, the same having been partially pushed down into the holder formed by the side pieces 41.

The cover can be unfolded and brought down over the open top of the body again 85 should it be desired to close the box, after first turning the flap 3 over and down into its former position between the top-edge portions of the sides 22.

Advertising matter can be printed on any 90 or all of the exposed surfaces of the closed box, as well as on the flap 3 and the card 44, and might be printed on both sides of said flap.

The flap 2 serves as a spacer for the sides 95 22 and upon which said sides are folded. The flap 24 constitutes a locking member for the tabs 20, and with the flap 25 a spacer for the ends 23. The flaps 16, 43, and 19 form spacers for the sides 22 at the end opposite to that which is provided with the flap 2. The tabs 20, being confined between the flap 24 and the adjacent side 22 which frictionally engage them, prevent the ends 23 from being pulled out of place. The 100 tongue 37, which is in the recess 36, prevents the innermost flap 27 from being pulled endwise out of place, while the frictional contact between the other flap 27 and the members on both sides thereof prevent said last-named flap from being pulled endways out of place, and the joint 35 holds said flaps in 105 parallel relation with each other and with the end 42 and the tongue or tongue piece. Thus it is seen that a strong bottom for the 110 box is produced, a bottom which is not liable to permit the contents of the box to drop through, that the end of the cover, which end forms the rear support when the box is open and disposed for display purposes, possesses 115 the required rigidity, and the box as a whole is stable in every respect, whether the same be closed or open, and when set up for the purpose of displaying said contents.

The flap 3 might be omitted, but the same 120 is valuable as a bearer of advertising matter.

What I claim as my invention, and desire to secure by Letters Patent, is—

1. As an improved article of manufacture, 130

a folding box comprising a body, and a cover attached to said body and adapted to be folded over one end of and beneath the body, said cover having members which 5 serve as a card holder when the cover is thus disposed.

2. The combination, in a folding box, with a body, of a cover attached at one end to one end of said body, said cover comprising a 10 top with sides, and end members, said top and sides being creased to enable said cover to be folded over one end of said body and beneath the same, and when so folded to form an inclined support for the body, and 15 a card holder at said end of the body.

3. The combination, in a folding box, with a body, of a cover attached at one end to one end of said body, said cover comprising a top with sides, and end members, said 20 top and sides being creased to enable said cover to be folded over one end of said body and beneath the same, with portions of said sides bent inwardly to form a card holder, said cover when so folded forming an inclined support for the body.

4. The combination, in a folded box, with a body comprising a bottom, side members attached at their under edges to the longitudinal edges of said bottom, end members 30 attached, each at one end, to the ends of one of said side members, a spacer attached to the under edge of one of said end members, a wide spacer attached at its upper edge to the upper edge of the other side member, 35 a narrow spacer attached to the under edge of said wide spacer, a wide spacer attached at one end to one end of said first-named wide spacer, and a narrow spacer articulated to the under edge of said second-named wide 40 spacer, of a cover attached directly to the upper edge of said first-named end member.

5. The combination, in a folding box, with a body comprising a bottom, side members attached at their under edges to the longitudinal edges of said bottom, end members 45 attached, each at one end, to the ends of one of said side members, a spacer attached to the under edge of one of said end members, tabs attached to the opposite ends of said end 50 members, a wide spacer attached at its upper edge to the upper edge of the other side member, a narrow spacer attached to the under edge of said wide spacer, a wide spacer attached at one end to one end of said 55 first-named wide spacer, and a narrow spacer attached to the under edge of said second-named wide spacer, of a cover attached to the upper edge of said first-named end member.

6. The combination, in a folding box, with a body comprising a bottom, side members attached at their under edges to the longitudinal edges of said bottom, end members attached, each at one end, to the ends of one of said side members, a spacer attached to the under edge of one of said end members, a wide spacer attached at its upper edge to the upper edge of the other side member, a narrow spacer attached to the under edge of said wide spacer, a wide spacer attached at one end to the one end of said first-named wide spacer, a narrow spacer attached to the under edge of said second-named wide spacer, and a display flap attached to the upper edge of said second-named wide 75 spacer, of a cover attached to the upper edge of said first-named end member.

7. The combination, in a folding box, with a body comprising a bottom provided with side members, one of which latter is provided with end members, a side-separating spacer attached to one of said end members, end-holding tabs attached to said end members, an end-separating spacer attached to one of the side members, an end-separating spacer attached to said first-named end-separating spacer, a side-separating spacer also attached to said first-named end-separating spacer, a side-separating spacer attached to said second-named side-separating 90 spacer, and a display flap attached directly to said second-named side-separating spacer, of a cover comprising a top attached directly to one of said end members, and provided with side members, said top and side 95 members being creased to enable said cover to be folded over one end of and beneath said body, an end member attached to said top at the free terminal thereof, a tongue-provided spacer, for the side members of said 100 cover, attached to said last-named end member, and other cover-side-member spacers attached to the cover-side members, one of said last-named spacers being recessed to receive the tongue of the tongue-provided 105 spacer.

8. The combination, in a folding box, with a body, of a cover attached at one end to one end of said body, and comprising a top and side members creased to permit the cover to be folded over one end and beneath the bottom of said body, said sides then being partly turned in beneath the bottom of said body.
